UNITED STATES PATENT OFFICE.

THOMAS DRAPER, OF MIDDLETOWN, CONNECTICUT, ASSIGNOR, BY MESNE ASSIGNMENTS, TO THE DRAPER & HALL CO., OF MIDDLETOWN, CONNECTICUT, A CORPORATION OF CONNECTICUT.

PRINTER'S COMPOSING-STICK.

No. 905,060.

Specification of Letters Patent.

Patented Nov. 24, 1908.

Application filed September 11, 1907. Serial No. 392,381.

To all whom it may concern:

Be it known that I, THOMAS DRAPER, a citizen of the United States, residing at Middletown, in the county of Middlesex and 5 State of Connecticut, have invented new and useful Improvements in Printers' Composing-Sticks, of which the following is a specification.

This invention relates to printers' composing sticks; and it has for its object to provide improved means whereby the stick may be quickly and accurately adjusted to lines of various lengths, giving a column of a predetermined width; further objects being to 15 simplify and improve the construction and operation of this class of devices.

With these and other ends in view which will readily appear as the nature of the invention is better understood, the same consists in the improved construction and novel 20 arrangement and combination of parts which will be hereinafter fully described and particularly pointed out in the claim.

In the accompanying drawing has been 25 illustrated a simple and preferred form of the invention; it being, however, understood that no limitation is necessarily made to the precise structural details therein exhibited, but that changes, alterations and modifications 30 within the scope of the invention may be resorted to when desired.

In the drawing, Figure 1 is a perspective view of a composing stick constructed in accordance with the invention. Fig. 2 is a 35 side elevation of the same. Fig. 3 is a transverse sectional view taken on the plane indicated by the line 3—3 in Fig. 2. Fig. 4 is a transverse sectional view taken on the plane indicated by the line 4—4 in Fig. 2.

40 Corresponding parts in the several figures are denoted by like characters of reference.

The invention is applicable to various kinds or types of composing sticks; and in the drawing it has been shown applied to 45 what is commercially known as the "Yankee" style of composing stick, of which 1 designates the base plate, 2 the end wall, 3 the back wall and 4 the knee, which latter includes the beveled side flange 5 which is 50 clamped adjustably upon the back wall 3 by means of a clamp 6 having a set screw 7, the point of which engages a recess 8 in the flange 5; it will be readily seen that by slightly loosening the set screw, the knee 55 may be shifted or moved to any desired

position where it may be securely retained by tightening the screw; the parts may be disassembled, if desired, by releasing the point of the screw from the recess 8.

The knee is provided with a recess 9 60 formed longitudinally in the upper surface thereof, and in said recess is suitably secured one end of a spring 10, the free end of which overhangs the back wall 3 of the stick and is formed with a knob or handle 65 11; said spring consisting of a flat leaf, the upper side of which normally lies flush with the upper side of the knee. The upper edge of the back wall 3 of the stick is provided with V-shaped notches 12 which are suitably 70 spaced to form a scale, the unit of which may be a pica em, or any other unit that may be desired; said scale being for convenience provided with graduation marks consisting of numerals, suitably spaced. The spring 75 10 is provided with a tooth 13 adapted for engagement with the notches 12.

The operation and advantages of this invention will be readily understood from the foregoing description taken in connection 80 with the drawings hereto annexed by those skilled in the art to which it appertains. When the set screw 7 is slightly loosened, the operator, by lifting the free end of the spring 10 to disengage the tooth 13 from 85 the notched wall of the stick, may quickly adjust the knee to the desired point, where it will be held securely by releasing the spring to permit the tooth 13 to engage one of the notches 12; the knee may thus be instantly adjusted to the position desired without resorting to the methods of measurement 90 ordinarily employed.

Having thus fully described the invention, what is claimed as new is:

95 A composing stick having its wall notched at its upper edge and provided with a graduated scale, an adjustable knee having a recess in its upper surface, a spring secured in the recess and lying flush with the outer 100 surface of said knee, said spring having a downwardly extending tooth to lock in the notches of the galley wall, and means for holding said knee in adjusted position.

In testimony whereof I affix my signature 105 in presence of two witnesses.

THOMAS DRAPER.
